BRUSH LOCK

Filed June 24, 1931

Joseph Bonardi

INVENTOR

BY *Victor J. Evans*
and Co.

ATTORNEY

UNITED STATES PATENT OFFICE

JOSEPH BONARDI, OF ROCK FALLS, ILLINOIS

BRUSH LOCK

Application filed June 24, 1931. Serial No. 546,571.

This invention relates to brush or buffer locks and has for the primary object, the provision of a simple and efficient means for detachably securing a brush or buffer to the arbor of a flexible shaft, wherein the rotation of the brush or buffer by the flexible shaft will aid in securing the brush and buffer to the arbor against accidental disconnection and which will permit easy and quick removal of the brush or buffer by rotating the latter in a reverse direction relative to the arbor, thus obviating the need or use of any type of tool to make the removal.

Another object of this invention is the provision of an improved bearing or journal between the arbor and handle of the brush which will reduce friction to a minimum.

A further object of this invention is the provision of a brush of the above stated character which will be simple, durable and efficient and which may be manufactured and sold at a comparatively low cost.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a side elevation partly in section illustrating a brush lock constructed in accordance with my invention.

Figure 2 is a sectional view taken on the line 2—2 of Figure 1.

Figure 3 is a fragmentary view partly in section illustrating the attaching medium and its means of attachment to the arbor.

Referring in detail to the drawing, the numeral 1 indicates a handle having a bore 2 one end of which is internally screw threaded to receive the screw threaded end of a shaft housing 3 in which is mounted a flexible shaft 4 of a conventional type. The bore 2 has a portion thereof enlarged to form a bearing or journal chamber 5 opening through one end of the handle and the last named end of the handle is enlarged to form a head 6 which is recessed as shown at 7 to

receive a brush mounting which will be hereinafter more fully described.

A sleeve 8 is located in the chamber 5 and has its ends flared to frictionally engage the walls of the chamber 5 and to provide raceways for balls 9 that engage bearing portions or cones 10 of an arbor 11. The arbor 11 extends through the sleeve and is rotatably supported by the balls so as to have free rotation with a minimum amount of friction and has one end socketed to receive the end of the flexible shaft 4 so that the arbor will be rotated by the rotation of the flexible shaft. The other end of the arbor 4 is reduced to form an extension 12 located concentrically of the head 6 and is screw threaded as shown at 13 and has threaded thereon an attaching medium 14. A washer 15 is mounted on the extension 12 against the attaching medium 14 and is held thereagainst by a nut 16 having threaded engagement with the extension. The washer 15 is preferably of the split or lock type to prevent the securing medium 14 from becoming accidentally disconnected from the extension 12.

One of the cones 10 of the arbor is formed integral therewith while the other cone is mounted upon the extension and removable therefrom as clearly shown in Figure 2.

Partially within the head 6 is a hand-hold 17, having a hub portion 18 which has a tapped connection with the extension 12 of the arbor, and rotates with said arbor when the parts are fully assembled. The walls of the part 17 are flared outwardly, and said part and the head of the handle can be grasped by one hand of the operator to hold the part 17 and arbor 11 from rotation.

A brush or buffer head 19 has one end enlarged as shown at 20 and provided with a centrally located recess 21 to receive the end of the extension 12. An attaching plate 22 is detachably secured to the enlarged end of the brush or buffer head 19 and practically closes the recesses 21 and is provided with a screw threaded opening to receive screw threads 23 forming an integral part of the attaching medium 14.

The brush or buffer carrying the attaching plate 22 is adapted to be threaded onto the

attaching medium 14 in the same direction as the brush or buffer rotates by the flexible shaft 4 or the arbor 11 so that during the use of the device the tendency is for the brush or buffer to thread onto the attaching medium, consequently obviating any possibility of the brush or buffer becoming accidentally disconnected from the arbor. To remove the brush or buffer, the flexible shaft 4 is held against rotation in the manner above described, and the brush or buffer rotated in a reverse direction. To return the brush to operative position this operation is reversed, with the brush turning in a clock-wise direction. The hand-hold 17 also encloses the hub 20, forming a shield therefor, and preventing objects from coming in contact therewith or getting caught thereon.

From the foregoing description taken in connection with the accompanying drawing, it will be noted that a very efficient means is provided for attaching a brush or buffer to an arbor driven from a flexible shaft and that the arbor is rotatably supported within a handle with a minimum amount of friction.

While I have shown and described the preferred embodiment of my invention, it will be understood that minor changes in construction, combination and arrangement of parts may be made without departing from the spirit and scope of my invention, as claimed.

Having thus described my invention, what I claim is:

1. A brush lock comprising a cylindrical handle provided with a head at one of its ends, an arbor rotatably mounted in said handle, a hand-hold connected with said arbor and forming an extension of said head, said head and hand-hold being jointly engageable by the hand of the operator to hold the hand-hold and arbor from rotation, and a brush assembly detachably connected with said arbor to rotate therewith.
2. A brush lock comprising a cylindrical handle provided at one of its ends with a head, an arbor rotatably mounted in said handle, a hollow hand-hold connected with the arbor and forming an extension of said handle, and a cylindrical brush assembly connected with said arbor, and having a part enclosed within said hand-hold and shielded thereby.

56 3. In testimony whereof I affix my signature.
JOSEPH BONARDI.
